WILLIAM L. WILLIAMS, OF NEW YORK, N. Y.

Letters Patent No. 88,250, dated March 23, 1869; antedated March 18, 1869.

IMPROVEMENT IN MACHINES FOR SPLITTING WOOD.

The Schedule referred to in these Letters Patent and making part of the same.

To all whom it may concern:

Be it known that I, WILLIAM L. WILLIAMS, of the city and State of New York, have invented, made, and applied to use a certain new and useful Improvement in Machines for Splitting Kindling-Wood; and I do hereby declare the following to be a full, clear, and exact description of the said invention, reference being had to the annexed drawing, making part of this specification, wherein—

Figure 1 is a plan of said machine;

Figure 2 is a vertical cross-section at the line *x x*; and

Figure 3 is a similar section at the line *y y*; and

Figure 4 is an elevation of the sliding bed and feeding-wheel.

Similar marks of reference denote the same parts.

Machines have heretofore been made for splitting kindling-wood, in which the wood is caused to move along through the feeding-trough by means of chains, but the concussion and the splinters of wood are apt to interfere with the chain operating satisfactorily.

The nature of my said invention consists in a pair of horizontal-toothed feeding-wheels, placed at the sides of the trough, and mounted so as to yield to inequalities in the wood that is fed along by them to the cutter, said feed taking place when the cutter is out of the wood. I also provide means for adjusting the plate that holds the wood down as the cutter rises.

In the drawing—

a represents the bed of the machine, upon which are placed two stationary side pieces, *b b*, forming a trough for the reception of the blocks of wood, placed up endwise within said trough.

Above the bed *a* is the frame *c*, carrying the shaft *d*, with its crank *e* and pitman *f*, to the sliding head-block *g*, that carries the cutting-knives *h*, that are placed diagonally to the trough *a b*, as seen in fig. 1.

The rotation of the shaft *d* causes the reciprocation of the knives *h*, and in splitting blocks of wood of usual length, it is not necessary for the knives to come within about two or three inches from the bed *a*; but if very short blocks were introduced, for making fine kindling-materials, the knives would not pass sufficiently far into the same to split them, and if the knife itself were raised or lowered, there would be difficulty in the adjustment, and risk of the parts becoming loose.

I therefore make use of a movable bottom, *k*, to the trough, held in place by ribs at the ends, taking against the end-portions of the bed *a*, as seen in the detached section, fig. 5.

This movable bottom, *k*, supports the short pieces of wood, and causes the knife to pass sufficiently near to the surface upon which they stand, to insure the splitting.

In order to accommodate the varying points at which the upper ends of the blocks of wood will stand in the trough, according to the length of the blocks, I make use of an adjustable plate, *i*, through slots in which, the knives *h* pass; and

l l are screws, that are actuated by the gearing *m* and cross-shaft *o*, so as to raise and lower the said plate *i* uniformly on the two sides, so that it shall remain parallel with the bed *a*.

The projecting portions of the plate *a* pass through slots in the frame *c*, and are guided thereby.

This adjustment may be applied to the frame carrying the rollers, as in my patent of December 12, 1865.

I provide side-bars *p* above the pieces *b b*, which side-bars *p* are attached in place by bolts *2 2*, at one end of the machine, and near the other end of the machine are standards *3 3*, between which, and said bars *p*, are springs, so that the bars *p* will yield to undue strain, laterally, that may be caused by the knives passing into the wood and spreading it.

The horizontal feed-wheels *q* are formed with pointed teeth projecting around the periphery, and the vertical shafts *4* pass through sliding beds *r*, that are fitted to move at right angles, or nearly so, to the trough, and these beds are formed with pendent arms *r'* that carry the cross-shaft *s*, upon which are the bevel-gears *t*, taking corresponding gears *u* upon the shafts *4*.

The gears *t* are fitted with sliding keys, pins, or feathers, so that they may move endwise of said shaft *s*, but be turned thereby; and

w is a ratchet-wheel, to which a lever, *5*, and pawl, *6*, are applied; and

7 is a connecting-rod to a crank-pin on the shaft *d*.

The parts are so placed that the wood is fed along by the wheels *q*, at a time when the knives are above the wood, and said feed-wheels stand still while the knives are splitting the wood.

The feed-wheels pass the wood forward to the cutters with regularity, and yield sufficiently to pass through large or closely-packed pieces, or spring up to maintain the hold upon smaller or less closely-packed pieces.

What I claim, and desire to secure by Letters Patent is—

1. The horizontal yielding and toothed feeding-wheels *q*, arranged at the sides of the feeding-trough, and actuated substantially as specified, to move the wood along when the knives are above said wood, as set forth.

2. The side-bars *p*, extending from end to end, or nearly so, of the trough *b*, and united by a bolt at the ends, where the wood is entered, and provided with springs near the other ends, for the purposes and as set forth.

3. The plate, or frame, adjusted by screws, as specified, in combination with the feeding-trough and reciprocating cutters, substantially as set forth.

In witness whereof, I have hereunto set my signature, this 12th day of August, 1868.

W. L. WILLIAMS.
